UNITED STATES PATENT OFFICE.

CHARLES V. ROTE, OF LANCASTER, PENNSYLVANIA, ASSIGNOR OF ONE-THIRD TO PARKE E. SHEE AND ONE-THIRD TO FREDERICK SHOFF, OF LANCASTER, PENNSYLVANIA.

DESIGN FOR A RAILWAY-CAR BODY.

No. 38,822.

Specification for Design.

Patented Sept. 17, 1907.

Application filed June 3, 1907. Serial No. 377,118. Term of patent 14 years.

To all whom it may concern:

Be it known that I, CHARLES V. ROTE, a citizen of the United States, residing at Lancaster, in the county of Lancaster and State of Pennsylvania, have invented a new, original, and ornamental Design for a Railway-Car Body, of which the following is a specification, reference being had therein to the accompanying drawing.

The figure is a perspective view of a railway car body, showing my new design.

I claim:

The ornamental design for a railway car body, as shown.

CHARLES V. ROTE.

Witnesses:

PARKE E. SHEE,
EDW. F. SMITH.
